SAMUEL R. SLAYMAKER, OF LANCASTER, AND ROBISON WALTER, OF MANHEIM, PENNSYLVANIA, ASSIGNORS TO UNITED STATES ASBESTOS COMPANY, OF MANHEIM, PENNSYLVANIA, A CORPORATION OF PENNSYLVANIA.

SEMIMETALLIC PACKING.

Application filed August 6, 1926. Serial No. 127,583.

Our invention consists in the novel features hereinafter described, reference being had to the accompanying drawing which shows the preferred form in which we have 5 embodied our invention, and a slight modification thereof, and the said invention is fully disclosed in the following description and claims.

Our invention consists in a novel semi-10 metallic packing, comprising among its members a channeled casing member formed of compressible material, as for example layers of asbestos cloth, cotton duck, or the like, with or without metallic wires twisted with 15 the yarn or otherwise incorporated, said layers being preferably "frictioned" with rubber or other vulcanizable material and vulcanized, although the casing member may be of plastic material molded and hardened 20 to the desired degree. On one face of this casing a channel is formed, the lateral faces of which are preferably disposed angularly to each other, so as to produce a reentrant wedge shaped recess or V-shaped recess in 25 cross section. This recess may be dry, but is preferably lubricated with graphite or other suitable material, and the casing is flexible so that it may be bent or curved into ring or spiral form with the channel on the 30 inside of the ring. Within the channel of the casing member is fitted a longitudinally extending metallic block member composed of non-friction metal preferably in a divided condition as wires twisted or braided or 35 otherwise assembled, or small pieces, blocks or slugs of metal, so arranged as not to interfere with the bending of the entire packing into ring or spiral form. This block member is also of wedge shape to fit the channel 40 and project slightly therefrom, and the longitudinal apex or inner edge of the block member is preferably formed of non-metallic material as fabric or composition with or without metallic wires, to facilitate the 45 proper sliding of the block member with respect to the casing member. The metal block member is preferably charged with lubricant, and the whole packing is held assembled in any desired manner which will 50 not interfere with the proper movement of the metallic block member in the channel for the proper functioning of the packing as by braiding any suitable material around it.

In the accompanying drawings,

Fig. 1 represents a piece of our improved 55 packing bent into ring form with the ends lapped.

Fig. 2 represents a cross section of the packing on the line 2—2 of Fig. 1.

Fig. 3 represents a view of a portion of the 60 packing before the braided cover is attached.

Fig. 4 represents a longitudinal section on the line 4—4 of Fig. 3, with the braided cover attached.

Fig. 5 is a longitudinal section on the line 65 5—5 of Fig. 6.

Fig. 6 represents a cross section of the construction shown in Fig. 5.

Referring to the accompanying drawings, 70 1 represents the channeled casing member, formed in this instance of layers of asbestos cloth with or without metallic wires indicated at 1^a, permanently united, which may be conveniently accomplished by frictioning the cloth with rubber or other vulcanizable material and vulcanizing the casing member, but this casing member may be formed in other ways. For example, the asbestos cloth may be united by other adhesive means, or the casing member may be formed 75 of duck or other cloth with or without metallic wires in layers united by rubber and vulcanized or united by other plastic material, or the casing member may be formed of a plastic material molded into the proper channeled shape and hardened to the desired degree, and where the casing member is so formed of plastic material, it may be reinforced in any desired way as by threads, fabric, or even 80 wire, if desired. 2 represents the longitudinal channel formed in one face of the casing member, and being preferably V-shaped or wedge shaped as shown. In any event, it is preferable to have the sides of 85 the channel inclined to each other and flared from the inside outwardly, to facilitate the relative movement of the metallic block member with respect thereto, but we prefer to make the channel in the form of a V in cross section. 3 represents the metallic 90 block member which is co-extensive longitudinally with the casing member, and is formed almost entirely of non-friction metal. The metal parts may be in the form of wires, 95 3^a, united by braiding, twisting, or in any other desired manner, and pressed into the proper form to fit the channel between the inclined faces thereof. Instead of having 100 105

the metallic portions of the block member extend to the inner edge or apex of the channel, this portion of the block member indicated at 4, and which we term for convenience the apex of the block member, is preferably formed of non-metallic material as fabric or compressible composition with or without metallic wires. The purpose of providing the metallic block member with the non-metallic flexible or compressible apex portion is to facilitate the proper sliding of the metal block member in a direction from and toward the casing member, in the channel of the latter. If the apex were of metal there would be variations in the density of the metal block as it compressed in use, and this is avoided by the provision of the non-metallic compressible or elastic apex portion. In other words, the metallic portion of the metal block member is capable of sliding in and out in the channel of the casing member, without materially varying its density at any point. While we have shown as our preferred construction the use of braided anti-friction metal wire, the metal block member could be formed in its metallic portions of solid pieces or slugs of metal, as indicated in Figs. 5 and 6, in which the corresponding portions of the packing shown in Figs. 1, 2 and 3 are given the same numerals with 100 added, to avoid unnecessary description.

In Figs. 5 and 6, the metallic portions of the block member indicated as a whole at 103, are composed of metal slugs or pieces, 103^a, so assembled as to permit of the bending, coiling, or spiraling of the packing, and the said block member is shown as provided with the non-metallic apex portion indicated at 104, fitting in the bottom of the recess, 102, in the casing member, 101. One reason why we prefer to construct the metallic block member of braided metal wire is, that it provides storage space for lubricant between the wires and adds to the effectiveness of the packing. The entire packing including the casing member and the metallic block member are preferably united by a cover or enclosing member indicated at 5 in Figs. 1 and 2. This cover may be conveniently formed by braiding with any suitable thread or material, but it is not essential, and the casing member and metallic block member may be united in any other suitable manner, which will not interfere with the proper movement of the metallic block member in the channel of the casing member, or the proper contact and functioning of the packing with respect to a rotating or sliding rod, which it may surround. The cover might be dispensed with altogether so far as the effective operation of the packing is concerned, but for commercial purposes it is desirable to unite the members of the

packing in a unitary structure for convenience in handling and transportation, and this is most conveniently done by a cover around them. A covering could be wound around them spirally, or they may be held together in any other desired manner as by threads more or less openly braided or surrounding the packing at intervals.

Our improved packing is manufactured in lengths of any desired extent, and in use a section is cut off sufficient to form a ring with butted or overlapped ends as preferred, or a spiral, to be put in a stuffing box around a sliding or rotating device, or rod, and compressed by the gland or follower of the stuffing box in the direction of the arrow at *a* in Fig. 2. The metallic block member cannot be crushed, but will slide in the direction of the arrow, *b*, in Fig. 2, into contact with the rod or the other device to be packed, which will revolve within it or slide through it effectively, while the escape of fluid, whether liquid or gaseous, is efficiently prevented.

As the metallic block member is at all times capable of movement inwardly as well as outwardly in the channel, 2, which is preferably although not necessarily lubricated, the effect of high pressure, liquid or gaseous material exerted on the packing in the direction of the arrow, *a*, would naturally tend to force the metallic block member into closer contact with the rod or other movable device to be packed, while when the pressure is withdrawn as on the return stroke of a piston, the reduction of pressure would permit the metallic block member to recede into the channel and relieve its friction on the movable rod or part to be packed. This action is termed "breathing" of the packing, and our improved packing is extremely efficient in providing for this "breathing" of the same.

As the face portions of the metallic block member become worn, and the glands or followers are drawn down to expand the packing laterally and keep it in fluid tight contact with the rod, it will be seen that the metallic block member slides outwardly in the direction of the arrow, *b*, in Fig. 2, and cannot be crushed or distorted, thus retaining all the ordinary advantages of the packing, and compensating for wear. By providing the metallic block member with a non-metallic apex portion, 4, the metallic portion, 3, is enabled to retain substantial uniform density throughout, notwithstanding the fact that the apex portion may be considerably compressed and distorted by reason of the fact that it occupies the narrowest portion of the channel, and while compressibility or elasticity of this apex portion facilitates the natural movements of the metallic portion in and out of the channel, or in other words the "breathing" of

the packing. If the metallic portion of the block member were carried to the extreme bottom or inner end of the channel, the compression of the packing in the stuffing box

5 would tend to pinch this portion increasing its density and interfering with the freedom of movement of the metallic block member with respect to the casing member.

What we claim and desire to secure by

10 Letters Patent is:—

1. The herein described packing comprising among its members a casing member composed mainly of non-metallic compressible material, and provided on one face with

15 a channel tapering inwardly in cross section, and having its lateral faces inclined to each other, of a metallic block member composed of non-friction metal in divided condition, the particles whereof are capable of move-

20 ment with respect to each other to permit of the coiling, spiraling, or bending of the packing, said block member having inclined lateral faces to fit the faces of the said channel, and a substantially triangular

25 mainly non-metallic member extending longitudinally of the block member and fitting the inner portion of said channel.

2. The herein described packing comprising among its members a casing member

30 formed mainly of non-metallic compressible material, and provided with a longitudinal channel on one face substantially V-shaped in cross section, a metallic block member composed substantially of non-friction metal

35 wire, and having inclined lateral faces to fit and slidingly engage the sides of the said channel, and a longitudinally extending compressible member engaged with the inner edge of the block member and fitting

40 the inner portion of said channel, said member being composed mainly of non-metallic compressible material.

3. The herein described packing comprising among its members a casing member

45 composed of layers of fabric united into a solid compressible body, and provided on one face with a substantially V-shaped longitudinal channel, and a substantially trapezoidal metallic block member composed of

50 non-friction metal in divided condition, and having a longitudinally disposed apex mem-

ber composed mainly of non-metallic material, said block member having its lateral faces tapered to fit and slidingly engage the side walls of said channel.

4. The herein described packing comprising among its members, a casing member composed of layers of asbestos woven fabric united by vulcanized material, and provided

5 with a substantially V-shaped longitudinal re-cess on one face, and a metallic block member formed separately therefrom, and comprising non-friction metal wires, and a longitudinally disposed substantially triangular

65 member composed mainly of non-metallic material, said block member having its lat-er faces disposed angularly to each other to fit movably in said channel, and means for retaining said members in associated re-lation.

5. The herein described packing comprising among its members, a casing member composed of layers of asbestos woven fabric united by vulcanized material, and provided

70 with a substantially V-shaped longitudinal recess on one face, and a metallic block member formed separately therefrom, and comprising non-friction metal wires, and a longitudinally disposed substantially trian-gular member composed mainly of non-me-

75 tallic material fitting the apex portion of said recess, said block member having its lat-er faces disposed angularly to each other to fit movably in said channel, and a braided covering surrounding said members

80 and holding them movably in assembled re-lation.

6. The herein described packing comprising a casing member composed of compressible material and provided on one face with

85 a channel substantially V-shaped in cross section, a substantially trapezoidal metallic block member fitting the outer portion of said channel and substantially triangular compressible member engaging the inner

90 face of said block member and fitting the apex portion of said channel.

In testimony whereof we affix our signatures.
